UNITED STATES PATENT OFFICE.

ARTHUR DANBY, OF PHILADELPHIA, PENNSYLVANIA, ASSIGNOR TO THE IVINS, DIETZ & METZGER COMPANY, OF SAME PLACE.

DESIGN FOR CARPET.

SPECIFICATION forming part of Design No. 26,781, dated March 16, 1897.

Application filed January 9, 1897. Serial No. 618,657. Term of patent 3½ years.

To all whom it may concern:

Be it known that I, ARTHUR DANBY, a subject of the Queen of Great Britain, residing at Philadelphia, county of Philadelphia, and 5 State of Pennsylvania, have invented and produced a new and original Design for Carpet Fabrics, of which the following is a full, clear, and exact description, reference being had to the accompanying drawings, which 10 form a part of this specification.

My design is suitable for carpet fabrics generally, but is particularly adapted to rugs.

The drawing shows one of the corners of a rug embodying my design. 15 The body A has a dark background relieved but slightly by plain finely-lined figures of similar color but different shade. Adjacent to the margin of the border B and at one point extending into the dark background for a considerable distance is a boldly 20 and distinctly, but irregularly, outlined field relieved by figures of different sizes and varieties, as shown. At the inner corner is a quarter-section of the central figure of the

rug, as shown, resembling in sharpness of 25 outline and arrangement of figures the portion of the body just described adjacent to border.

The border B presents the general effect of different-sized figures connected and surrounded by irregularly-extending lines of the same general width and color, flanked by rows of small ornamental figures of the same general size and appearance as shown.

Having now fully described my design, 35 what I claim is—

1. In a design for a carpet fabric, the body A, substantially as shown.
2. In a design for a carpet fabric, the border B, substantially as shown. 40
3. The design for a carpet fabric comprising the body A and the border B.

In testimony of which invention I have hereunto set my hand.

ARTHUR DANBY.
